(57) **CLAIM**

The ornamental design for a portion of a tenderizer, as shown and described.

DESCRIPTION

FIG. 1 is a top perspective view of a portion of a tenderizer showing the new design; and,

FIG. 2 is top plan view thereof.

The broken lines in the figures illustrate portions of the portion of a tenderizer that form no part of the claimed design.

1 Claim, 2 Drawing Sheets

FIG. 1

FIG. 2
